UNITED STATES PATENT OFFICE

DAVID REITER, OF WOODSIDE, NEW YORK

DENTAL HAND-PIECE GUARD

Application filed November 1, 1929. Serial No. 404,078.

The invention relates to dental instruments, particularly to safety devices, and has for its general object the provision of a guard adapted for use in connection with a hand-piece for the purpose of preventing contact with and injury to the cheek or tongue of the patient when grinding a tooth.

It is well known that the ordinary hand-piece is used for grinding, a small grinding disk being employed. Very frequently it occurs that the grinding disk or wheel may slip off from the tooth worked upon and cause laceration of the patient's cheek or tongue. It is with these facts in view that I have devised the present invention which has for an important object the provision of a guard which may be simply slipped onto or clamped upon the hand-piece without altering the construction of the latter and which embodies a member which substantially encloses the disk and which will therefore at all times prevent contact thereof with the cheek or tongue.

Another object is to provide a device of this character in which the guard is movably mounted so as to be swung partly away from the grinding wheel when such is desired.

Another important object is to provide a device of this character in which the guard is movably mounted with respect to the hand-piece when carried thereby so that the guard may be placed over a tooth and the hand-piece moved with respect thereto to bring the grinding disk into contact with the tooth without moving the guard itself, while if the operator slips the guard will immediately move relatively to the hand-piece and enclose the disk for the protection of the patient.

Another object of the invention is to provide a device of this character equipped with means for supplying water to the grinding disk as is necessary to prevent excessive heat from friction with a tooth.

Another object is to provide a device of this character which may be manufactured and sold as a complete and separate entity adapted to be used as an attachment to already existing hand-pieces.

A further object is to provide a guard

structure which may be readily sterilized and kept in a thoroughly sanitary condition.

An additional object is to provide a device of this type which will be simple and inexpensive to make, easy to use, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a side elevation of my device showing it in association with a dental hand-piece which is illustrated in dot and dash lines.

Figure 2 is an end view,

Figure 3 is a top plan view, and

Figure 4 is a cross section taken on the line 4—4 of Figure 1.

Referring more particularly to the drawings the letter A designates a portion of a dental hand-piece which when used for grinding carries a rotary abrasive disk B. In carrying out my invention I provide a complete structure here shown as comprising a clamp or clip 10 represented as of cylindrical shape and formed as a split sleeve so that it may be slipped onto or otherwise engaged upon the hand-piece. The material of this sleeve is resilient so that it will grip the hand-piece closely and maintain itself in proper position thereon.

Suitably secured upon this sleeve at a location preferably opposite the split is a bracket 11 provided at one end with spaced upstanding ears 12 and having its other end offset and forwardly extended to provide a stop member 13.

I also provide an elongated arm for a lever 14 provided with ears 15 preferably straddling the ears 12 and pivoted thereto as by a suitable pin 16 so as to be capable of swinging movement. A spring 17 surrounds the pin and has one end engaging against the attaching portion of the bracket 11 and its other end bearing against the underside of the arm or lever 14 for the pur-

pose of normally holding the latter in flat contacting engagement with the stop 13. This arm 14 carries the guard 18 to which it is secured in any desired manner as for example by soldering or by means of the rivets indicated at 19, such a detail being immaterial. This guard is of a casing-like construction so as to surround the grinding disk B which may, however, be seen by the operator owing to the provision of a series of observation holes 20. This guard is here disclosed as having a curved lower portion 21 between depending extensions 22. These extensions are adapted to be engaged with the teeth 15 for the purpose of guiding the device when in use.

An important feature is the provision of means for conducting water to the grinding disk for keeping it cool and in carrying this out I provide a rubber tube 23 held within clips 24 on the sleeve 10, it being a convenient plan to form these clips integrally on the sleeve by the simple expedient of cutting the metal and bending it into the desired shape as clearly indicated. On that edge of the guard toward the sleeve I also provide a clip 25 which is likewise preferably formed integrally therewith by cutting and bending and which holds the end portion of the tube, the end extending partly within the confines of the guard so that water will be directed onto the disk. Any suitable means, not shown, may be employed for feeding water through the tube and this water may be permitted 35 to flow in any desired quantity, either drop by drop or as a small stream. Only a small amount is, however, necessary and the compression of the tube by the resilient clips will constrict its wall or passage so that there will 40 really be only a very small flow.

Assuming that the device has been engaged upon the hand-piece, it will be apparent that when a tooth is to be ground the guard is inserted within the patient's mouth with the extensions 22 straddling the tooth. After the proper position has been found, it is merely necessary for the operator to bear down somewhat on the forward end of the hand-piece, that is to say tilt it downwardly or upwardly depending upon which jaw is being worked upon, so as to move the grinding disk with respect to the guard and into contact with the tooth. When this is done the arm or lever 14 carrying the guard assumes 55 an inclined position with respect to the hand-piece, in opposition to the action of the spring 17 which always tends to maintain the guard in enclosing relation to the disk. The necessary water is permitted to flow as above described. If at any time the operator slips the spring 17 will act to return the arm 14 to its normal position with the guard extending around the disk so that this disk cannot 60 come into contact with the tongue or cheek 65 of the patient under any circumstances. Owing

to the provision of the observation holes the progress of the work may be easily ascertained. At any time such is desired the operator may press upon the projecting end of the lever or arm 14 and swing the guard away from the disk, as for example when it is desired to change from one disk to another.

From the foregoing description and a study of the drawings it will be apparent that I have thus provided a simply constructed and inexpensive device which will be a great safeguard during the carrying out of dental work. The device is easily attached to already existing hand-pieces and may be manufactured and sold as a complete assembly or entity. As all the parts are of metal it is clear that the device may be easily washed and sterilized so as to remain always in sanitary condition. As the construction is rugged it is evident that there is nothing to get out of order and that it should possess great durability. It is thought that the construction, operation and advantages should be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A guard attachment for a dental hand-piece carrying a grinding disk, comprising a member adapted to be engaged upon the hand-piece, an arm pivoted thereon, and a guard carried by said arm and arranged in substantially enclosing relation to the disk, said guard being provided with a series of observation holes at its top and sides and provided in its bottom with an opening, said arm being movable to extend the disk to said opening.

2. A guard attachment for a dental hand-piece carrying a grinding disk, comprising a member adapted to be engaged upon the hand-piece, an arm pivoted thereon, a guard carried by said arm and arranged in normally enclosing relation to the disk, the guard having spaced prongs thereon engageable with teeth at the sides of one worked upon, a water conducting tube carried by said member and projecting into said guard adjacent the disk, and a clip on the guard compressingly holding the tube.

3. A protective device for a dental hand-piece equipped with a grinding disk, comprising a member adapted to be engaged upon

the hand-piece, a support on said member, a movable spring pressed arm pivoted on said support, a guard carried by said arm and normally substantially enclosing the disk, 5 and means for limiting movement of the arm in one direction.

4. A device of the character described comprising a sleeve member adapted for engagement upon a dental hand-piece equipped with 10 a grinding disk, a support on said sleeve, an arm pivoted intermediate its ends upon said support and having one end serving as a handle, and a guard carried by the other end of the arm and normally enclosing the disk, 15 the guard being of substantially semi-cylindrical shape with its sides prolonged to define spaced prongs, the prongs being connected for a portion of their width by a transverse concaved element.

20 5. A device of the character described comprising a sleeve member adapted for engagement upon a dental hand-piece equipped with a grinding disk, a support on said sleeve, an arm pivoted intermediate its ends upon said 25 support and having one end serving as a handle, a guard carried by the other end of the arm and normally enclosing the disk, spring means normally maintaining said arm in position with the guard enclosing the disk, 30 and a stop for limiting movement of the arm in one direction.

6. A device of the character described comprising a sleeve member adapted for engagement upon a dental hand-piece equipped with 35 a grinding disk, a support on said sleeve, an arm pivoted intermediate its ends upon said support and having one end serving as a handle, a guard carried by the other end of the arm and normally enclosing the disk, spring 40 means normally maintaining said arm in position with the guard enclosing the disk, and a stop for limiting movement of the arm in one direction, said stop being formed as an offset extension on the support.

45 In testimony whereof I affix my signature.
DAVID REITER.
